UNITED STATES PATENT OFFICE.

CHARLES V. JAMESON, OF CHICAGO, ILLINOIS, ASSIGNOR OF ONE-EIGHTH TO HENRY E. WEISERT, ONE-EIGHTH TO ARTHUR BISSELL; AND THREE-EIGHTHS TO JAMES CURTISS, ALL OF CHICAGO, ILLINOIS.

PLAYER-PIANO.

1,137,404.

Specification of Letters Patent. Patented Apr. 27, 1915.

Application filed May 24, 1912. Serial No. 699,361.

To all whom it may concern:

Be it known that I, CHARLES V. JAMESON, a citizen of the United States of America, and a resident of Chicago, county of Cook, 5 and State of Illinois, have invented certain new and useful Improvements in Player-Pianos, of which the following is a specification.

My invention relates to player pianos and 10 has for its object improvements in the devices for holding the perforated sheet which controls the pneumatics. In the present case these devices are located behind the fall board and are raised and lowered.

15 In the accompanying drawings Figure 1 is a vertical longitudinal section of part of a piano showing the devices in elevation and in operating position; Fig. 2 is a transverse section on line 2—2 of Fig. 1; Fig. 3 is a 20 similar section with the devices in their lower position; Fig. 4 is a plan of the devices shown at the right of Fig. 1; Fig. 5 is a section on line 5—5 of Fig. 4; Fig. 6 is a perspective view of the locking devices for 25 the drive shaft.

Supported on a shelf P^1 in the piano casting P , are brackets 10, the upper ends of which are located behind the lower part of the front panel P^2 . Pivoted at 11 on the 30 upper ends of the brackets 10 are arms 12 which support the tracker bar 13, the receiving roll 14, and the pins 15 for holding the roll of perforated paper. The arms 12 are of peculiar shape necessary in fitting 35 them to the position in which they are located behind the fall board F . One part 16 of the arms 12 is hook shaped to clear the lower edge of the panel P^2 .

Secured in a fixed position to the arm 12 40 at the right hand is a bar 17 which is held far enough from the arm 12 to provide several inches of space. In this space are supported clutch and rewind mechanisms which are of a well known character and need not 45 be described.

Pivoted to the arm 12 on the left and to the bar 17 on the right, are links 18 which have their other ends pivoted to arms 19 secured to the shaft 20. On the end of the 50 shaft 20 is a small gear 21 which meshes with a larger gear 22, and engaging the gear 22 is a rack 23 supported in guides 24 on the piano casing P . Pivoted at 25 on the casing P is a hand lever 26, and connected be-

tween pins on this lever and on the rack 23 55 is a link 27. The connections are such that when the hand lever 26 is moved on its pivot 25 the rack is moved in its guides to turn the gears 22 and 21. The extreme positions of these parts are shown in full and dotted 60 lines in Fig. 4. Turning the gear 21 turns the shaft 20 and moves the arms 19 between the positions shown in Fig. 2 and Fig. 3. As the arms 19 are connected through links 18 to the arms 12, the rotation of the shaft 65 20 serves to raise or lower the tracker bar and its associated parts.

In their lower position the tracker bar and its associated parts are concealed within the piano behind the fall board. When they are 70 being elevated they pass through an opening cut in the horizontal shelf between the bottom of the panel P and the tops of the fall board F . This opening is normally closed by a door 29 which automatically 75 rises and falls when the tracker bar is raised and lowered.

The mechanism for operating the paper feed is driven from the motor B through the chain 30, the shaft 31, chain 32 and gears 80 33. When the tracker bar and its associated parts are lowered from the position shown in Fig. 2 to the position shown in Fig. 3, the sprocket wheel at the upper end of the chain 32 moves near to, and slightly back of the 85 sprocket 34 at the other end of the chain, which sprocket 34 is on the shaft 31. In this position the chain 32 is slack and a turning of the shaft 31 and sprocket 34 would be liable to displace it. To prevent this I attach to a convenient place a spring 35. When the tracker bar is lowered this spring rests in the teeth of the sprocket 34 by its own tension and prevents the sprocket and its shaft 31 from being turned. When the shaft 95 20 is turned to raise the tracker bar, the adjacent arm 19 engages a bent end of the spring 35 and pulls it away from the teeth of the sprocket 34, thus leaving that sprocket free to drive the paper feed. This mechanism is shown in Fig. 6, but is omitted from the other figures for the sake of clearness.

What I claim is:—

1. The combination with the front panel and the fall board of a piano, of a pivotally 105 supported tracker bar, and means by which the bar may be moved from a position below the panel and behind the fall board to

1. a position in front of the panel and above the fall board.
2. In a piano, a front panel and a fall board, a tracker bar having an operative position in front of the panel and somewhat above the fall board, and means by which the tracker bar may be moved to a position within the piano below the panel and behind the fall board.
3. The combination with a piano casing having a front panel and a fall board, of a tracker bar normally concealed within the casing below the panel and behind the fall board, and means for moving the tracker bar to and supporting it at a position exterior to the casing.
4. The combination with a piano casing having a front casing and a fall board, of a tracker bar normally concealed within the casing below the panel and behind the fall board, a pivotal support for the tracker bar, an opening through the casing in front of the panel and normally closed by a door, and means for moving the tracker bar on its pivotal support so as to cause it to raise the door and pass through said opening to the exterior of the casing.
5. The combination with a piano casing having a front panel, a fall board and an opening between the lower part of the panel and the fall board, and a door adapted to close said opening, of a tracker bar and a pivotal support therefor located within the casing, means for moving the tracker bar on its pivotal support so that it will open the door and pass to the exterior of the casing, and means for moving a perforated sheet over the tracker bar when in its exterior position.
6. The combination with a piano casing having a front panel, a fall board, and a door normally closing an opening in the casing between the panel and the fall board, of a tracker bar located within the casing and below the door, a hand operated device located outside of the casing, and connections from the hand operated device to the tracker bar for raising the latter through said opening.
7. The combination with a piano casing 50 having a front panel, a fall board, and a door normally closing an opening in the casing between the panel and the fall board, of a tracker bar within the casing and below the door, and connections extending to the exterior of the casing for raising the tracker bar through said opening.
8. The combination with a piano casing 60 having a front panel, a fall board, and a door normally closing an opening in the casing between the panel and the fall board, of a tracker bar below the door, a pivotal support for the tracker bar, connections extending to the exterior of the casing for raising the tracker bar through said opening and means for moving a perforated sheet over the tracker bar when in raised position.
9. The combination with a piano casing, 70 of a tracker bar normally within the casing, means controlled from the exterior of the casing for moving the tracker bar through an opening in the casing to the exterior thereof, a driving mechanism for moving a perforated sheet over the tracker bar when 75 said bar is in its exterior position, and means for locking the driving mechanism against operation when the tracker bar is in its interior position.
10. The combination with a tracker bar, 80 devices for moving it from one position to another, and a driving mechanism for moving a perforated sheet over the tracker bar, of locking devices for the driving mechanism, said locking devices being operated by 85 the movement of the tracker bar.
11. The combination with the piano casing, and a fall board, of a tracker bar normally concealed within the casing and behind the fall board, and means for moving 90 the tracker bar to and supporting it at a position exterior to the casing.

Signed at Chicago, Illinois this 22 day of May 1912.

CHARLES V. JAMESON.
